DUAL LEVER PRY TYPE LID LIFTER

Arthur E. Hopmann, Maplewood, Mo.

Application September 24, 1951, Serial No. 247,942

3 Claims. (Cl. 81—3.1)

1

The present invention relates to certain new and useful improvements in hand tools and implements and has more particular reference to an especially constructed implement which lends itself for multipurpose use when employed in connection with caps, lids and similar closures on food and commodity containers, for example, jars, bottles and the like.

It goes without saying that the art to which the invention relates is highly developed and unceasingly active and upon making a survey thereof one would find innumerable as well as varied styles and forms of tools referred to as jar cap wrenches and lid and cap lifters and removers. With a view toward advancing the art and adding thereto a worthy contribution the instant invention has been evolved and produced. In carrying out the principles of the invention a preferred embodiment of the same embodies a pair of duplicate lever units. Each unit has a handle portion and corresponding ends of the respective handle portions are linked and properly pivoted together for operational association. Novel cap wrenching and lifting components are provided on the outer free end portions of the respective lever units.

More specifically, the invention has to do with the stated lever units therein intermediate portions have segmental toothed grips and right angularly disposed adapter flanges, the flanges being in a plane with each other and nicely adapted to rest on the top portion of a screw cap to effectively apply the toothed cap wrenching grips.

A further object is to provide additional grips and these are disposed outwardly of the cap wrenching grips or jaws and are so designed that they cooperate intimately with the rim portion of a friction held lid and perform as lifters and serve to pry the lid loose without distorting the lid and so that it may be easily taken off with one's fingers.

Other objects and advantages will become more readily apparent from the following description and the accompanying sheet of illustrative drawings.

In the accompanying sheet of drawings where-in like numerals are employed to designate like parts throughout the views:

Figure 1 is a bottom plan view of a lid removing tool or implement constructed in accordance with the principles of the invention and showing the wrenching jaws as well as the hook-shaped lid lifters.

Figure 2 is a central longitudinal section taken on the plane of the section line 2—2 of Figure 1 with the position of the tool in reverse to that shown in Figure 1.

Figure 3 is a top plan view on a small scale showing the manner in which the tool is employed as a jar cap wrench.

2

Figure 4 is an enlarged view with the jar and cap in elevation and with the tool portions in section, the view being on the plane of the line 4—4 of Figure 3, looking in the direction of the arrows.

Figure 5 is a bottom plan view showing the manner in which the tool is employed as a friction lid lifter and remover.

Figure 6 is a view showing the tool in edge elevation, said view being based on Figure 5 with the jar and friction cap appearing fragmentarily in elevation.

Referring now to Figure 1, observing what may be said to be the bottom or underside of the tool, the duplicate coplanar lever units are denoted by the numerals 8 and 10 respectively. Corresponding end portions 12—12 are hingedly or pivotally connected at 14—14 with an intervening assembling and connecting link or plate 16. The portions of the units adjacent to the pivotal connections provide handles 18—18 and they have serpentine bends which provide convenient finger grips. The outer free end portions of the lever units are fashioned into duplicate especially designed prying implements or lifters and for convenience each lifter is denoted generally by the numeral 20. Actually, what happens is that the extreme outer ends are curved inwardly toward each other and are thus formed into coplanar return bends which may be conveniently referred to as hooks 22—22. The beak or bill portions 24—24 of the respective hooks are directed inwardly toward each other and these are used as piloting and prying claws in the manner shown in Figures 5 and 6 where for example each bill portion fits into the space (see Fig. 6) 26 which exists between the shoulder 28 and lip 30. The shoulder is on the jar 32 and the lip on the friction held lid or cap 34. Of course, all sorts of instruments are used such as screw driver bits, knife blades, beer can punches and what not, for prying one side of a lid open in an obvious fashion. Here, the lever units straddle the neck of the jar and hence the bill portions of the hooks are perched on the shoulder 28 at substantially diametrically opposite points to bring about a double acting lifting result. Not only are the bill portions of the hooks desirable in piloting and locating the lever units, they are immediately associated with opposed neck embracing jaws 36—36 having longitudinally curved edge portions 38—38 which more or less conform to the curved shape of neck of the jar. Then, too, in addition to these conforming grips 36—36 there are inwardly projecting opposed V-shaped projections provided and these are slightly elevated above the plane of said hooks and are denoted by the numerals 40—40 and are in opposed relation and they are lifting elements proper. In other words, the jaws 36—36 with their edges 38

3

fit in the space 26 and against the neck of the jar as shown best in dotted lines in Figure 5. The bill or beak portions 24 serve as fulcruming elements and they coact timely with the complements 38, 38 and 40 do the actual lifting by prying the flange portions 39 of the cap or lid 34 up and off the neck of the jar in an obvious manner. Of course, there are those who instead of lifting the handles of tool or implement upwardly will force the handles downwardly whereupon the hooks will do the lifting and the adjacent gripping portions will then perform as the fulcrum members. Since no two people perform an operation with a tool precisely alike, the technique of use is not to be dwelled upon here. Only the constructional characteristics are significant.

The intermediate portions of the lever units are fashioned into special curvate bends 42-42 which are considerably greater in cross-section than the relatively thin cross-section of the features just referred to in detail. The portions 42-42 also have opposed curvate inner edge surfaces and these are formed with teeth 44-44 providing toothed jaws which may be actually referred to as cap wrenching and removing jaws. In addition, these jaws have relatively thin segmental flat flanges 46-46 which are in a plane with each other and serve as adapters. That is to say, they are adapted to rest on the top portion of the screw cap 48 shown in Figures 3 and 4. Here, a screw threaded portion 50 is provided with a knurled gripping edge 52 for screwing and unscrewing the cap. The jar or container is denoted by the numeral 54. The manner in which the flanges rest atop the cap is shown in Figures 3 and 4 and it will be obvious that by squeezing the lever units together and holding the same firmly the jaw wrenches come effectively into play. As a matter of fact, the extended hooked free end portions of the respective levers may also be used wherever necessary to assist in forcing and holding the lever units firmly together and against the cap which is to be unscrewed. It follows, therefore, that the lever units have common handle means 18-18 at their pivoted ends while the free end portions which constitute lifting hooks for prying lids off also may serve, under certain circumstances, as handle means. This means that placing the toothed segmental grips intermediate the ends of the respective levers, they are in an ideal position to permit over-all and satisfactory use of the levers.

Generically, it will be understood that the overall instrumentality is characterized by duplicate lever units hinged together at corresponding ends with the adjacent portions constituting handles and with the intermediate portions having opposed gripping and removing devices and the outer free end portions having gripping and removing devices. Specifically, the first devices are toothed jar cap wrenches while the devices at the free ends are jar straddling, fulcruming and prying jaws.

Minor changes in shape, size, materials and rearrangement of parts may be resorted to in actual practice provided no departure is made from the invention as claimed.

Having described the invention, what is claimed as new is:

1. A lid lifting and removing implement comprising a pair of opposed duplicate levers hinged together at corresponding ends and connected together at free end portions with return bends, said

4

return bends defining hooks, said hooks having bill portions and said bill portions being adapted to pilot themselves into an existing space between a friction held lid and a shoulder on a jar whereby they may then serve as both fulcruming and lifting members, the portions of the respective levers adjacent said hooks having longitudinally curved edges conformable with adjacent portions of the neck of the jar and being adapted to fit in said space and providing opposed jaws which may be used either as fulcruming members or lid lifting members as the case may be.

2. A lid lifting tool for friction-held container lids comprising a pair of coplanar duplicate levers having serpentine handles hingedly connected at corresponding ends and having their opposite ends movable toward and from each other in a manner to effectively embrace jar necks of varying diameters, the latter ends being curved inwardly toward each other in a plane with each other and in the same plane with said levers and terminating in coplanar return bends defining fulcruming and lifting hooks, said hooks embodying bill portions of restricted cross-sectional thickness which are thus adapted to readily pilot themselves into an existing space between a lid and an underlying shoulder on the associated jar when said levers are pressed toward each other, the inner opposite longitudinal edge portions of said levers spaced inwardly from said bill portions being longitudinally curved and providing jar neck embracing jaws which act simultaneously with said hooks, said jaws being of a cross-sectional thickness conformable with the cross-section thickness of said hooks so that they enter the stated space and are allowed to fulcrum on said shoulder, whereby said lid may be pried loose and forced off of the jar in substantially intact form, permitting the lid to be handily replaced when desired.

3. A lid lifting tool for friction-held container lids comprising a pair of coplanar duplicate levers having serpentine handles hingedly connected at corresponding ends and having their opposite ends movable toward and from each other in a manner to effectively embrace jar necks of varying diameters, the latter ends being curved inwardly toward each other in a plane with each other and in the same plane with said levers and terminating in coplanar return bends defining fulcruming and lifting hooks, said hooks embodying bill portions, the inwardly facing longitudinal edge portions of said levers being longitudinally curved and providing a pair of embracing jaws, the latter being opposed to each other and spaced inwardly from the hooks.

ARTHUR E. HOPMANN.
